UNITED STATES PATENT OFFICE.

ROBERT B. FERGUSON, OF HOWELL, MICHIGAN, ASSIGNOR TO G. E. HARPHAM, OF LOS ANGELES, CALIFORNIA.

COMBINATION PLIERS.

Application filed May 13, 1920. Serial No. 381,008.

To all whom it may concern:

Be it known that I, ROBERT B. FERGUSON, a citizen of the United States, residing at Howell, county of Livingston, State of Michigan, have invented a certain new and useful Improvement in Combination Pliers, and declare the following to be a full, clear, and exact description of the same, such as will enable others skilled in the art to which it pertains to make and use the same, reference being had to the accompanying drawings, which form a part of this specification.

This invention relates to combination pliers, and the object of the invention is to provide a pair of pliers having the combined utility of a pair of pliers and a wrench. A further object of the invention is to provide a device of the character described having a solid and a stamped handle, each provided with a jaw, the stamped handle being adapted to fit over the other and being pivoted to a member movable longitudinally of the said solid handle whereby the jaws may be spaced apart any desired distance, within the limits of the device. A still further object of the invention is to provide a pair of pliers in which one handle is movable longitudinally of the other handle by a worm and rack, the said handle being provided with jaws spaced apart or brought together by rotation of the worm and the faces of the jaws extending in parallel relation when the handles are brought together. These objects and the several novel features of the invention are hereinafter more fully described and claimed, and the preferred form of construction by which these objects are attained is shown in the accompanying drawings in which—

Figure 1 is an elevation of a pair of pliers embodying my invention,

Fig. 2 is a view similar to Fig. 1 showing the jaws open,

Fig. 3 is a section through Fig. 2 showing the construction,

Fig. 4 is a section taken on line 4—4 of Fig. 1,

Fig. 5 is a section taken on line 5—5 of Fig. 1.

Fig. 6 is a section taken on line 6—6 of Fig. 1,

Fig. 7 is a section taken on line 7—7 of Fig. 2, and

Fig. 8 is a perspective view of the movable member adapted to ride in the grooves in the solid handle.

The pliers consist of a handle 1 which is made of a solid piece of metal and is provided with a gripping jaw 2 extending at an angle to the outer end thereof. The handle is cut away at 3 on each side to provide a narrow part in which the teeth 4 are cut. In this cutaway portion 3 is also a groove 5 on each side of the handle 1, shown more particularly in Fig. 5; and as shown more particularly in Fig. 8, I provide a member 6 having inturned flanges 7 and 8 adapted to ride in the grooves 5 in the handle. Supported in this member 6 is a shaft 9 secured therein by pins 10, and rotatably mounted on the shaft 9 is a worm 11 meshing with the teeth 4 in the handle. The member 6 is provided with two outwardly extending lugs or ears 12 and 13 which are apertured to receive the pivot pin 14 by means of which the hollow U-shaped handle 15 is pivoted on the member 6. Between the members 12 and 13 of the member 6, I provide a short piece of tubing 16 which holds the members 12 and 13 in spaced relation as shown more particularly in Fig. 7. The handle 15 is made preferably of sheet metal bent to a U-shape in cross-section and provided with outwardly extending ends 17 which fit over the handle 1 and which are pivoted to the members 12 and 13 by the pin 14. The outwardly extending end 17 is also provided with a gripping jaw 18 opposite the gripping jaw 2, the member 18 being formed as shown in Fig. 6 and cut away at the side to receive the members 17 which are secured thereto by the rivet 19.

In operation the handles 1 and 15 are separated as shown in Fig. 2, which separates the jaws 2 and 18 of the device, and by closing the handles as shown in Fig. 1 the jaws are caused to grip. When the device is to be used as a nut wrench the gripping jaws are separated or brought together by rotation of the worm 11, it being necessary that the jaws be spaced apart approximately the diameter of the nut, at which time the handles may be brought together causing the jaws of the pliers to engage two opposite faces of the nut. It will be noted that at any adjustment of the handle 15 on the handle 1 when the device is closed, the upper and lower jaws always extend in parallel relation thereby making the device very efficient for gripping a nut or the like. This device may also be used wherever ordinary

pliers may be used, and in addition will grip larger objects more firmly on account of the ability of adjusting one jaw longitudinally in relation to the other jaw. Thus it will be seen that my pliers will grip a small hairpin with the same ease and efficiency that it will grip a large nut or the like.

From the foregoing description it becomes evident that the device, while of a somewhat simple nature, is very efficient in operation, of comparatively cheap manufacturing cost, will not easily get out of order, and provides a strong and efficient device which accomplishes the objects desired.

Having thus briefly described my invention, its utility and mode of operation, what I claim and desire to secure by Letters Patent of the United States is—

1. In combination pliers, a solid one-piece handle having a gripping jaw extending outwardly at an angle from the upper end thereof, a rack formed on one side thereof, the handle being provided with a pair of oppositely disposed grooves, a movable member riding in the said grooves, a worm rotatably mounted in the said movable member and engaging the rack, and a second handle U-shaped in cross-section fitting over the first-named handle and pivotally mounted upon the said movable member.

2. In combination pliers, a one-piece handle having a gripping jaw formed at the upper end thereof and extending outwardly at an angle to the body thereof, a rack formed in the handle, said handle being provided with a groove on each side adjacent

the rack, a movable member having in-turned ends riding in the said grooves, a shaft stationarily mounted in the said movable member, a worm rotatably mounted on the said shaft and meshing in the said rack, and a second handle formed of sheet metal pivoted to the movable member and extending over the first-named handle.

3. In combination pliers, a handle having a gripping jaw extending outwardly at an angle to the upper end thereof, a rack on one side of the handle, the handle being grooved on each side adjacent the rack, a movable member riding in the said grooves, a worm rotatably mounted in the movable member and meshing in the said rack, and a second handle U-shaped in cross-section and extending over the first-named handle at the end and carrying a companion jaw to that of the first-named handle.

4. In combination pliers, a handle having a gripping jaw extending outwardly at an angle to the upper end thereof, a rack in one face of the handle, the handle being grooved on each side adjacent the rack, a U-shaped member having in-turned ends riding in the said grooves, a worm rotatably mounted in the U-shaped member and meshing in the rack, a pair of lugs extending outwardly from the U-shaped member, and a second handle formed of sheet metal and having outwardly extending ends pivotally secured to the said lugs and provided with a gripping jaw secured therebetween.

In testimony whereof, I sign this specification.

ROBERT B. FERGUSON,
